Primary Examiner — Deanna L Pratt(74) Attorney, Agent, or Firm — Ladas & Parry LLP(57) CLAIM

The ornamental design for a makeup mirror, as shown and described.

DESCRIPTION

FIG. 1 is a front elevational view of a makeup mirror showing my new design;

FIG. 2 is a rear elevational view thereof;

FIG. 3 is a left side elevational view thereof;

FIG. 4 is a right side elevational view thereof;

FIG. 5 is a top plan view thereof;

FIG. 6 is a bottom plan view thereof;

FIG. 7 is a perspective view thereof; and,

FIG. 8 is another perspective view thereof shown in an alternative position.

The broken lines in the drawings illustrate portions of the makeup mirror that form no part of the claimed design.
